(No Model.)

J. PEARD.
SCHOOL DESK.

No. 268,275.

Patented Nov. 28, 1882.

UNITED STATES PATENT OFFICE.

JOHN PEARD, OF BROOKLYN, NEW YORK.

SCHOOL-DESK.

SPECIFICATION forming part of Letters Patent No. 268,275, dated November 28, 1882.

Application filed April 15, 1882. (No model.)

To all whom it may concern:

Be it known that I, JOHN PEARD, a citizen of the United States, residing at Brooklyn, in the county of Kings and State of New York, 5 have invented new and useful Improvements in School Desks and Seats, of which the following is a specification.

This invention consists in the combination, with a school desk and seat, of ledges formed 10 in the standards of the desk and seat at a distance below the seat and below the lower edge of the back, a horizontal bottom board supported by said ledges, a back board rising from the inner edge of the bottom board to the back 15 of the seat, and a front board rising from the outer edge of the bottom board, so that a book-box is obtained which is deep enough for an atlas or other large book or a slate, and from which said books can be readily taken 20 out. With this book-box and the back of the seat is combined a hinged cover to protect the books against dust.

In the accompanying drawings, Figure 1 represents a transverse vertical section. Fig. 2 25 is a rear elevation.

Similar letters indicate corresponding parts.

In the drawings, the letter A designates one of the standards or side pieces which support the seat B, the back C, and the desk D. In 30 the example shown in the drawings the seat swings on pivots a, so that it can be turned up against the back, and the desk swings on pivots b, so that it can be turned to the position shown in dotted lines in Fig. 1.

35 In desks of this class as heretofore constructed the standards are provided with ledges which are on a level with the lower edge of the back, and which serve to support a horizontal board, from the outer edge of which 40 rises a front board, so as to produce a book-box, the inner side or back of which is formed by the back C of the seat. This book-box, however, cannot be made deep enough for an atlas or other article of similar size without 45 exposing these articles to injury from the motions of the desk, because if it should be made deep enough the desk could not be turned up, and even if the desk is turned down to its working position these large books could not

be introduced into or removed from the box. 50 Furthermore, the book-box, being open at the top, forms a receptacle for dust, and the articles contained therein are not protected against dust or other impurities. In order to overcome this difficulty, I form on the standards A, at a level considerably below the lower edge of the back C, the ledges E, which serve 55 to support the bottom e of the book-box F. From the inner edge of this bottom rises the board d and from its outer edge the board e 60 of the book-box, the upper edge of said back board, d, being firmly secured to the back C of the seat. To the back C is secured by hinges f the cover g in such a position that the same, when closed, assumes an inclined 65 position and remains closed by its inherent gravity.

In order to reach the contents of the book-box the cover must first be raised.

By these means I am enabled to form a 70 book-box of sufficient depth for the largest books which are usually in the hands of scholars, and when the cover is closed down the contents of the book-box are protected against dust or other impurities. At the same time 75 sufficient room is left for the movement of the desk. It will also be seen that the back C is braced by the back board, d, of the book-box, and that the latter can be entirely closed.

What I claim as new, and desire to secure by 80 Letters Patent, is—

1. In combination with a pivoted seat, B, a back, C, and a centrally-pivoted desk, D, in rear of the seat, the supporting-standards provided with ledges E at a distance below 85 the seat, the book-box consisting of the bottom e, board or wall e, and board or wall d, extending vertically from the ledges and connected with the back C, whereby a deep vertical book-box is formed, closed on all sides, 90 and the back of the seat strengthened and the desk free to turn on its pivot without injuring books contained in the box, substantially as described.

2. In combination with the back C, seat 95 B, centrally-pivoted desk D, and standards A, the ledges E on the standards below the pivotal point of the seat, the bottom e, and

vertical boards *d e*, each of the latter being about equal in length and supported by the ledges below the seat, to form a book-box beneath the centrally-pivoted desk, with a cover hinged upon rear of the seat-back, the construction and arrangement being substantially as and for the purpose described.

In testimony whereof I have hereunto set my hand and seal in the presence of two subscribing witnesses.

JOHN PEARD. [L. S.]
